UNITED STATES PATENT OFFICE.

JULIUS ANDRADE, OF CLEVELAND, OHIO, ASSIGNOR TO CHANDLER MOTOR CAR COMPANY, OF CLEVELAND, OHIO, A CORPORATION OF OHIO.

DESIGN FOR A RADIATOR SHELL.

Application filed June 27, 1925. Serial No. 13,934. Term of patent 14 years.

To all whom it may concern:

Be it known that I, JULIUS ANDRADE, a citizen of the United States, and resident of Cleveland, in the county of Cuyahoga and State of Ohio, have invented a new, original, and ornamental Design for a Radiator Shell, of which the following is a specification, reference being had to the accompanying drawing, forming part thereof.

Fig. 1 is a front elevational view and

Fig. 2 is a side elevational view of a design for a radiator shell, showing my new design.

I claim:

The ornamental design for a radiator shell, as shown.

In testimony whereof I have hereunto set my hand.

JULIUS ANDRADE.
